UNITED STATES PATENT OFFICE.

JAMES H. ALEXANDER, OF PHILADELPHIA, PENNSYLVANIA.

DESIGN FOR A BUCKET-EAR.

SPECIFICATION forming part of Design No. 16,348, dated October 27, 1885.

Application filed July 11, 1885. Serial No. 171,385. Term of patent 14 years.

To all whom it may concern:

Be it known that I, JAMES H. ALEXANDER, a citizen of the United States, residing at Philadelphia, in the county of Philadelphia and State of Pennsylvania, have invented a certain new and useful Design for Bucket-Ears; and I do hereby declare the following to be a full, clear, and exact description of the invention, reference being had to the accompanying drawing, which forms part of this specification, in which the figure is a plan or front view of a bucket ear embodying my design.

The design constituting my invention consists, broadly, of a bucket ear composed of a rivet-plate and a bail-eye, the former having a straight top edge, the two parallel side edges, and a bottom edge composed of two curved or ogee lines meeting at the middle in a point.

My invention consists, furthermore, of a bucket-ear having the contour of the rivet-plate formed as above specified, and having upon its face raised flanges at the edges, an ornamental raised flange crossing its face vertically, and ornamental bosses surrounding its rivet-holes.

My invention also consists in the shape and surface ornamentation of the shank or bail-eye of a bucket-ear, all as hereinafter described and claimed.

My design relates to the plate or flange, and also the shank. The upper edge of the plate A consists of two straight lines, which are continuations of the edge lines of the shank. The side edges of the flange are straight for the greater part of their length, and are at right angles to the top edges. The bottom edge consists of two curved lines or ogee curves, which meet at the middle in a point, B. The flange A has a raised edge, C, and

the surface around the rivet-holes is raised and formed in the shape of stars, or with points d d. The metal of the flange between the point B and the base of the shank is also raised, forming a rib, E. This rib is of the peculiar shape shown, its two side edges consisting each of two curved lines, e e. The surface of this rib has indentations or intaglio marks in it, as shown. The shank around the eye F has a series of notches or radial grooves, f f, and below the bail-eye the shank is formed with a raised surface, which is preferably in the configuration of a fanciful initial letter N.

What I claim as my design is—

1. In a design for a bucket-ear, the plate A and the shank, the plate having a straight upper edge, two parallel side edges, and a bottom edge composed of two ogee curves uniting in a depending point, as shown and described. 55

2. In a design for a bucket-ear, the plate and shank, said plate having the outline described and shown, and having a raised flange on its edge following said outline, as shown and described. 6c

3. The design for a bucket-ear, consisting of a plate and a shank, the plate having a flat top edge, two parallel side edges, and a bottom edge composed of two ogee curves uniting in a depending point, said edges having raised flanges, and the face of the plate having star-like bosses surrounding its rivet holes, and with a transverse raised flange, as shown and described. 70

In testimony that I claim the foregoing I have hereunto set my hand this 1st day of July, A. D. 1885.

JAMES H. ALEXANDER.
